UNITED STATES PATENT OFFICE.

WILLIAM V. LEWIS, OF KANSAS CITY, MISSOURI.

DRIER.

1,409,740.

Specification of Letters Patent. Patented Mar. 14, 1922.

Application filed January 20, 1920. Serial No. 352,862.

To all whom it may concern:

Be it known that I, WILLIAM V. LEWIS, a citizen of Great Britain, and resident of Kansas City, in the county of Jackson and State of Missouri, have invented a certain new and useful Improvement in Driers, of which the following is a complete specification.

The present invention relates to drying machines, and aims to provide an improved drier construction adapted to produce a more effective treatment in the drying and sterilizing of various kinds of granular materials, such as cereals, flour, bran, and also shredded materials, as well as chemical substances in certain forms, etc.

Accordingly I have devised an improved drier construction in which I arrange the heating chamber as an interior compartment and provide an exterior housing forming a drying chamber entirely surrounding the interior chamber, together with means for maintaining a continuous circulation of the material to be treated through the drying chamber in a direction about the heating chamber.

In carrying out this construction I provide an interior fixed heating chamber arranged substantially centrally within a drying chamber, in connection with which I provide a mechanical operating means which serves to alternately deposit the material being dried upon the upper surface of the heating chamber and thereafter remove said material from said upper surface of the chamber, thus in effect subjecting all of the material under treatment to a substantially even and uniform drying action without danger of burning or parching the material.

It is also sought to provide an improved construction of the above character in which provision is also made for preventing the formation of any cakes or lumps in the material during its course through the drying chamber.

Further features of improvement lie in the form and arrangement of the connections for the supply of heat, as well as in the peculiar arrangement and construction of the drive mechanism for operating the drier.

With these general objects in view the invention will now be described by reference to the accompanying drawings illustrating one form of embodiment of the improvement after which the novel features therein

will be set forth and particularly pointed out in the appended claims.

In the drawings—

Figure 1 is a side elevation illustrating a drier construction embodying the present improvements;

Figure 2 is a plan view of the same;

Figures 3 and 4 are sectional end elevations of the opposite ends of the drier, the same being shown on a larger scale, and representing sections taken on the lines 3—3 and 4—4, respectively, of Figure 1;

Figure 5 is an enlarged vertical sectional view taken on the line 5—5 of Figure 2; 70

Figure 6 is a vertical sectional view taken on the line 6—6 of Figure 1;

Figure 7 is an enlarged sectional view taken on the line 7—7 of Figure 2; and

Figure 8 is an elevation showing one end 75 portion of the rotary member which operates within the drying chamber.

Referring now to the said drawings in detail, these show the main heating chamber as formed by a central cylinder 9, the opposite ends of which are fitted within threaded recesses formed in a pair of cap or head castings 10. Each of these castings 10 is mounted upon the inner end of a tubular supporting member 11, and retained thereon by means of a lock nut 12, the outer ends of said tubular members 11 being held in fixed position in a suitable supporting frame-work 13, there being two of said frameworks 13, one opposite each end of the drier as illustrated in Figures 1 and 2. Fitted within one of the tubular members 11, is a steam inlet pipe connection 14 which is adapted to inject a supply of steam within one end of the cylinder 9, as illustrated in Figure 7. The other tubular member 11 is fitted with a steam outlet pipe 15, having a downwardly extending siphon portion 16 at its inner end within the cylinder 9, as shown in Figure 5. Each of the pipes 14 and 15 is equipped with a suitable regulating valve 17.

An exterior housing structure is provided for forming a drying chamber 18 entirely surrounding the heating chamber formed by the cylinder 9, this housing structure comprising a rectangular portion 19 enclosing the upper half of the heating chamber, and a semi-cylindrical portion 20 opposite the lower half of the said heating chamber. A second semi-cylindrical shell 21 is mounted 110 outside the shell 20, forming a space 22 be-

tween these two housing sections 20 and 21 which space is utilized for the arrangement of a set of auxiliary heating pipes 23, into which steam is admitted from a second steam supply pipe 24 at the inlet end of the drier as shown in Figure 3, these auxiliary pipes communicating with an outlet pipe 25 at the opposite end of the drier as shown in Figure 4. A similar set of auxiliary heating pipes 23' is arranged within the upper portion of the drying chamber 18, these pipes also communicating with the inlet and outlet steam connections 24, 25, just described.

The drier is supported by the frameworks 13 at its opposite ends, in more or less inclined position, according to the conditions and the character of the material being treated, a moderate degree of inclination being shown in Figure 1. The elevated end 20 of the drier, as thus arranged, may be termed the receiving end, and is provided with a receiving hopper 26 for the feeding of the material into the drying chamber. The lower end of the apparatus is provided 25 with a discharge outlet 27 communicating with the bottom of the drying chamber 18, and extending through the cylindrical shell 21, as shown in Figure 6. The rectangular portion 19 of the housing structure is further 30 provided with a vapor hood 28 communicating with the upper portion of the drying chamber 18 and extending in upwardly converging form, as shown in Figures 1 and 2, to suitable outlet 29, the communicating passage 35 between said hood and drying chamber extending substantially the full length of the drier.

The end wall of the exterior housing structure is made in sections, the lower sections 40 of which are formed as bearing standards 30 (see Figures 5 and 7), which provide bearings for the opposite ends of a rotating member for maintaining the circulation of the material within the drying chamber, as 45 will now be described.

This rotating member comprises a pair of skeleton or spider castings 31 at its opposite ends, each of these castings 31 having a hub sleeve 32 which is adapted to be journaled 50 upon the corresponding tubular member 11 and within the bearing portion of the corresponding bearing standard 30. At its outer end each hub sleeve 32 has keyed there-to a drive sprocket wheel 33 over which is 55 trained a drive chain 34 driven from a sprocket wheel 35. The two sprocket wheels 35 are mounted upon a countershaft 36 extending longitudinally of the drier and having its opposite ends journaled in bearings 60 in the upper ends of the frameworks 13, the middle portion of said shaft being supported in a bearing at the top of a similar framework 13' at the middle of the drier as shown in Figures 1 and 2. One end of the shaft 36 65 is provided with a bevel gear 37 meshing

with a bevel pinion 38 on a transverse shaft 39 mounted in bearing brackets 40 at the corresponding end of the drier, the shaft 39 being adapted to be driven in any suitable manner as by means of a belt applied to a 70 pulley 41 on said shaft 39.

Referring now more especially to Figures 5 and 6, the skeleton or spider members 31 are shown as connected by a series of longitudinally extending angle members 42, which are secured by means of suitable fastening means 43 to lugs 44 projecting inwardly from the members 31. These longitudinal angle members 42 serve as the supporting means for a series of specially formed flights 80 which project inwardly in the direction of the cylinder 9 for the purpose of engaging the material within the drying chamber 18 and agitating or mixing the same as well as maintaining a circulation thereof about said cylinder 9. Certain of these flights 45 are of plate form attached by suitable fastenings 45' to the angle members 42, the free portions of said flights 45 extending inwardly and being bent backwardly with reference to the 90 direction of rotation of the rotary member (as indicated by the arrows in Figure 6), so that the inner edges of the flights 45 barely touch the surface of the cylinder 9. The rest of the flights, 46, have their attached portions of the same form as the flights 45 and their free projecting portions extending in the same manner and at the same angle as the flights 45, but the free projecting portions of these flights 46 comprise a finger 100 structure, as best illustrated in Figure 5 for the purpose of more effectively and thoroughly mixing and stirring up the material and preventing the formation of any cakes or lumps therein. Preferably the 105 flights 46 are provided with a plurality of fingers 47 made in sections having slots 48 and bolts 49, whereby the length of these fingers may be appropriately adjusted for taking up the wear thereon as often as necessary. The series of the flights 45 and flights 46 are also arranged in successively staggered and in partially overlapping relation with reference to the length of the drier. By reference to Figure 8 it will also be seen 115 that the flights 46 alternate with the flights 45, the two forms of said flights being, therefore, substantially equal in number. In one side of the drier, preferably on the side opposite from the hood 28, I provide a 120 pair of openings in the face of the rectangular portion 19 of the exterior housing, which openings are sealed by means of removable plates 50, thereby affording access to the interior of the drying chamber 18 whenever 125 necessary for making inspection or repairs. It will accordingly be apparent that I have provided an efficient and comparatively simple arrangement and construction for carrying out the proposed object of the in- 130

vention. The operation of the rotary member with its flights 45 and 46, is such as to alternately pick up the material in the chamber 18 and carry the same over on to 5 the top surface of the cylinder 9 leaving a portion of the material deposited at different points along this top surface of said cylinder 9 which is picked up by the succeeding flights and swept off of the cylinder and 10 back into the chamber 18 on the opposite side of said cylinder. This maintains a constant movement and circulation of the material in the chamber 18, the action of the fingers 47 serving to break up any cakes 15 or lumps starting to form in the material, and the combined action of the flights 45 and 46 being to subject the material to an even and uniform treatment wherein it is not allowed to remain in contact with the 20 cylinder 9 long enough to be burnt or scorched. This operation of the drier construction is made possible by the provision of a fixed interior heating chamber surrounded by an exterior drying chamber, and 25 the heat being supplied to the interior chamber by means of a fixed pair of supply connections 14 and 15 while the only moving parts are those comprising the rotary member carrying the flights and operating about 30 the fixed axis of the tubular members 11 which support the cylinder 9. From this it is apparent that both the main and the auxiliary steam pipes comprise fixed and permanent parts having no movable joints what- 35 soever, such as are apt to give trouble by leaking or otherwise getting out of order. The provision of an auxiliary heating means affords a further important advantage by enabling the heating action to be properly 40 regulated according to conditions, and it being also apparent that the main heating chamber within the cylinder 9 or the auxiliary heating system afforded by the pipes 23 and 23' may be operated together or sepa- 45 rately and independently, as desired. It is also to be noted that the main heating chamber as well as the auxiliary pipe connections are so arranged as to siphon off all condensation collecting therein, and that there is 50 no dead end to the drier. A more efficient drying action is also obtained by virtue of the drying chamber being provided with a passage communicating with the vapor hood throughout the entire length of the drying 55 chamber. A part of the efficiency is also due to the operation of the finger structure of the flights 46, whereby the material is prevented from caking and is therefore presented evenly and thoroughly to the drying 60 action of the heat. The arrangement of the drive mechanism is very simple and effective, and the application of the drive to both ends of the drier distributes equally the power required for its operation.

65 While I have illustrated and described what I now regard as constituting the preferred form of construction for embodying the improvement, I desire to reserve the right to make such changes or modifications as may fairly fall within the scope of the following claims.

What I claim is:

1. A drier construction comprising an interior heating chamber, an exterior housing forming a drying chamber surrounding 75 said heating chamber, and a rotary member within said drying chamber provided with a plurality of flights arranged in staggered relation and operating to alternately deposit the material being treated upon the 80 upper surface of said heating chamber and thereafter remove said material therefrom.

2. A drier construction comprising a fixed cylinder forming an interior heating chamber, an exterior housing forming a 85 drying chamber surrounding said heating chamber and a rotary member operating about the axis of said cylinder and provided with a plurality of flights arranged in staggered relation and operating to alternately 90 deposit the material being treated upon the upper surface of said heating chamber and thereafter remove said material therefrom.

3. A drier construction comprising a fixed cylinder forming an interior heating chamber, an exterior housing forming a drying chamber surrounding said heating chamber, means for admitting steam axially within one end of said cylinder and a siphon outlet connection leading axially from the opposite end of said cylinder, and a rotary member operating about the axis of said cylinder and provided with a plurality of flights arranged in staggered relation and operating to alternately deposit the material 95 being treated upon the upper surface of said heating chamber and thereafter remove said material therefrom.

4. A drier construction comprising an interior heating chamber, an exterior housing forming a drying chamber surrounding said heating chamber, and a rotary member within said drying chamber provided with a plurality of flights arranged in staggered relation and operating to alternately deposit 110 the material being treated upon the upper surface of said heating chamber and thereafter remove said material therefrom, certain of said flights comprising a finger structure adapted to break any cakes or lumps forming in said drying chamber.

5. A drier construction comprising an interior heating chamber, an exterior housing forming a drying chamber surrounding said heating chamber, and a rotary member within said drying chamber provided with a plurality of flights arranged in staggered relation and operating to alternately deposit 115 the material being treated upon the upper surface of said heating chamber and there- 120

125

after remove said material therefrom, certain of said flights having inwardly projecting adjustable fingers adapted to break up any cakes or lumps forming in said 5 drying chamber.

6. A drier construction comprising an interior heating chamber, an exterior housing forming a drying chamber surrounding said heating chamber, an upwardly converging 10 vapor hood communicating with the upper portion of said drying chamber, and means operating within said drying chamber to alternately deposit the material being treated upon the upper surface of said heating 15 chamber and thereafter remove said material therefrom.

7. A drier construction comprising an interior heating chamber, an exterior housing forming a drying chamber surrounding said 20 heating chamber, means rotating within said drying chamber and around said heating chamber for causing a circulation of the material being treated around said heating chamber, and supplemental heating connections 25 extending through said drying chamber.

8. A drier construction comprising a fixed cylinder forming an interior heating chamber, an exterior housing forming a drying 30 chamber surrounding said cylinder, a rotary member provided with flights for maintaining a circulation of the material being treated around said cylinder, said rotary member having hub sleeves provided with

bearings in the ends of said housing, and 35 fixed supporting members projecting axially through said sleeves in position for supporting the ends of said cylinder.

9. A drier construction comprising a fixed cylinder forming an interior heating chamber, an exterior housing forming a closed drying chamber surrounding said cylinder, a rotary member provided with flights for maintaining a circulation of the material being treated around said cylinder, said rotary member having hub sleeves provided with bearings in the ends of said housing, and means associated with the outer end of sleeves for rotating said member. 40

10. A drier construction comprising a fixed cylinder forming an interior heating chamber, an exterior housing forming a closed drying chamber surrounding said cylinder, a rotary member provided with flights for maintaining a circulation of the material being treated around said cylinder, said rotary member having hub sleeves provided with bearings in the ends of said housing, tubular supporting members projecting axially through said sleeves in position for supporting said ends of said cylinder, and steam inlet and outlet connections mounted within said supporting members at the opposite ends of said cylinder, respectively. 55 60 65

In witness whereof I affix my signature.

WILLIAM V. LEWIS.
